(57) **CLAIM**

The ornamental design for a display screen with animated icon, as shown and described.

DESCRIPTION

FIG. 1 is the first image in a sequence for a display screen with animated icon showing my new design.

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof; and,

FIG. 11 is the eleventh image thereof.

The appearance of the animated icon sequentially transitions between the images shown in FIGS. 1-11. The process or period in which one image transitions to another forms no part of the claimed design. The broken line showings of a portion of the runner and the display screen are for environmental purposes only and form no part of the claimed design.
